UNITED STATES PATENT OFFICE.

JOHN LOFGREN, OF CHICAGO, ILLINOIS, ASSIGNOR TO RALCO MANUFACTURING CO., OF CHICAGO, ILLINOIS, A CORPORATION OF ILLINOIS.

COMBINATION SAFETY SWITCH AND RECEPTACLE.

1,347,345.

Specification of Letters Patent.

Patented July 20, 1920.

Application filed December 26, 1918. Serial No. 268,311.

To all whom it may concern:

Be it known that I, JOHN LOFGREN, a citizen of the United States, residing at Chicago, in the county of Cook and State 5 of Illinois, have invented a certain new and useful Combination Safety Switch and Receptacle, of which the following is a specification.

My invention is embodied in a combined 10 switch and receptacle, the general object of which is to prevent misoperation of the parts and to prevent their operation in improper sequence. In installing electric translating devices, especially portable or 15 removable ones, it is common practice to employ a plug and receptacle as a connector for establishing electrical connection between the translating device and the supply conductors. Good practice demands that a 20 service switch be interposed between the connector and the leading-in wires; also that the switch should be open whenever the plug is being inserted or withdrawn from the receptacle. But users of translating de- 25 vices are often careless or ignorant of the demands of good practice and it is very common for the operator to withdraw or insert the plug while the service switch is closed. This frequently causes arcing, which 30 endangers the apparatus and may even injure the operator. One of the objects of my invention is to make it impossible for the operator to insert or withdraw the plug unless the switch is open. Ordinarily the 35 service switch is an independent piece of apparatus from the receptacle and is sometimes installed at a distance from it. One of the contributory objects of my invention is to combine them so that they may consti- 40 tute a single piece of apparatus. Safety is the underlying purpose of the invention and in order to provide safety it is one of the objects of the invention to inclose the switch within a box and operate it from a 45 point outside of the box, so that if there is any arcing it will occur within the box and hence be relatively harmless. With this in mind I provide a door for the box and provide mechanism which will hold the door 50 closed until after the plug has been withdrawn, and the switch opened. Another object is to provide means by which the switch will be locked open so long as the door remains open. In the form selected to illus- 55 trate the invention the plug is inserted by

a straight-in push. In this connection it is my purpose to provide means for preventing the reversal of the plug, the purpose being to insure that the conductors in the cord or cable will always be connected to the proper respective supply conductors. Another object is to provide means whereby the plug will, if only partially inserted or withdrawn from the receptacle, prevent the switch from being closed. Other contributory objects will become apparent as the description proceeds.

In the accompanying drawings—

Figure 1 is a front elevation of apparatus embodying the invention, the box being shown in vertical section and the plug and receptacle also being shown chiefly in vertical section.

Fig. 2 is a perspective view illustrating the coöperation of constituent parts of the device.

Fig. 3 is a plan section showing the receptacle and bracket and parts of the receptacle.

Fig. 4 is a side elevation of the complete apparatus, the box and its door being in section.

Fig. 5 is similar to Fig. 4 except that the parts are shown in changed position.

Like reference numerals denote like parts throughout the several views.

In the illustrated form of the invention there is a box 1 which is intended to be mounted in fixed position. It is provided with a door 2 in front which is hinged at the upper end upon a pintle 3. A panel 4 of slate or other insulating material is fastened at the back of the box for supporting the service switch. This is illustrated as a single throw, three pole switch having three switch blades 6, 7 and 8 adapted to engage three stationary contacts 9, 10 and 11 respectively, to which are fastened three leading-in wires 12, 13, 14 respectively. It will be understood, however, that while I have illustrated a three wire system the same principle would apply to a system having more or less than three wires. The switch is operated by a handle 16 and the switch blades or arms are pivoted to the terminals 17, 18, 19, these being electrically connected to the conductors 20, 21 and 22, respectively which lead to sockets 23, 24, 25, respectively, mounted in the receptacle block 26. Block 26 consists of porcelain or

other insulating material and is supported upon a bracket 27 within the box. The precise form of the parts thus far described is immaterial, the point being that the switch 5 is mounted within the box and connected to the terminals of the receptacle, which is also carried by the box and preferably within it.

The plug consists in the present case, of 10 a block 30 of porcelain or other insulating material mounted within a shell 31 having a clamp 32 by which it may be connected to a flexible conduit 33. The conductors 34, 35, 36 which are incased within the sheath 15 of the conduit 33 are electrically connected to the pins 37, 38, 39 respectively, which are adapted to fit into the sockets 23, 24, 25, respectively to make electrical connections therewith.

At the side of the shell 31 there is formed 20 a lug 40 which is adapted to pass through the slot 41 formed in the bottom of the box. As this slot affords the only entrance for the lug, it prevents the plug from being inserted in any position but the right one to connect the proper conductors in the conduit 25 to the proper poles of the switch. Hence it may be said that the plug with its lug 40 is non-reversible.

Journalized near the bottom of the box is 30 a rock shaft 43 operated by a hand lever 44 located outside of the box as best shown in Fig. 1. Fastened to this shaft inside of the box is an arm 45 which is bifurcated at the 35 upper end to engage the switch handle 16. Thus the switch may be operated from a point outside of the box by operating handle 44. The rock shaft also has an arm 46 fastened to it which carries a dog 47 so placed 40 as to move into and out of the path of the lug 40 in harmony with the movements of the rock shaft and switch. The construction is such that when the switch is closed the dog will block the path of the lug, preventing the plug being inserted if out of the 45 receptacle, and preventing the plug being withdrawn if within the receptacle. If the plug is not pushed completely "home" in the receptacle the dog will strike the side of 50 the lug and prevent the switch from being closed. Thus it will be seen that the plug is 55 cannot be withdrawn unless the switch is open nor can it be inserted unless the switch is open, and the switch cannot be closed unless the plug is inserted to the full and proper distance.

Now, referring to the lockout, whereby the switch is prevented from closing when the plug is not in position in the receptacle; an 60 arm 50 is pivoted to a bracket 51 extending forward from the back of the box. This arm has a shoulder 52 adapted, when lowered, to drop behind the arm 46 and prevent the rock shaft from being rotated in a direction to close the switch. A lug 54 is

formed on the side of arm 50 in such manner that when the plug is in position in the receptacle the lug 54 will engage lug 54 and hold the lockout arm 50 up in non-acting position, but when the plug is withdrawn 70 it will permit said arm to drop. If the switch operating arm 45 is in a position corresponding to the closed position of the switch the shoulder 52 will drop onto the upper end of arm 46 and be supported by it. 75 If, however, the arm 45 moves the switch to open position the arm 46 will pass to the front of shoulder 52, thus permitting said shoulder to drop behind arm 46 and lock the switch open. Hence, the switch cannot 80 be again closed until the plug has been reinserted and the lug 54 has engaged the lug 54 and raised the lockout arm high enough to permit the arm 46 to clear the shoulder 52. 85

The mechanism for holding the door locked includes a hook 56 adapted to be engaged by a hook 57 formed at the outer end of arm 50. When the plug is in position in the receptacle it holds the arm 50 sufficiently elevated to engage hook 56 and hold the door locked. When the plug is withdrawn, arm 50 will drop far enough to clear the hook 56 before the shoulder 52 on said arm will contact the upper end of the arm 95 46. Thus the withdrawal of the plug will unlock the door.

I have provided means for requiring the door to be closed before the switch can be moved from open to closed position. This 100 mechanism includes a latch 60, pivoted to the bracket 61, fastened to the back of the box near the top. Said latch has a shoulder 62 adapted to drop behind the horizontal portion 63 of the arm 45 when the latter is 105 moved forward far enough to open the switch. A bracket 64 is mounted on the inside of the door near the hinge and is so positioned that when the door is closed the bracket will hold the latch high enough to 110 clear the horizontal portion 63 of arm 45, and permit the switch to move to closed position. If the door is open, latch 62 will rest upon the horizontal portion 63 so that the moment it passes beyond shoulder 62, 115 said shoulder will drop back of it and lock it in open position.

Operation: Let it be assumed that the parts are assembled as shown in Figs. 1 and 4, the switch being closed, the door closed 120 and the plug in position. The lug 40 holds lug 54 elevated so that hook 57 will engage the hook 56 and hold the door locked. The dog 47 will also block the path of lug 40 and prevent the withdrawal of the plug. 125 Hence if it is desired to withdraw the plug or open the door it is first necessary to throw the handle 44 over and open the switch. This causes the dog 47 to move to one side out of the path of lug 40. It is then possi- 130

ble to withdraw the plug, whereupon the arm 50 will drop sufficiently to cause the hook 57 to disengage the hook 56. Consequently, the door is now unlocked and may 5 be opened. The lowering of arm 50 causes the shoulder 52 to drop back of the arm 46 and lock the switch open. Furthermore, the opening of the door permits the shoulder 62 to drop behind the horizontal portion 10 63 of the arm 45, so that the switch will now be locked open by two separate and independent mechanisms. The advantage of the latch 60 is that it prevents the plug from being inserted and the switch subsequently 15 closed while the door is open. It compels the attendant to operate the parts in the proper sequence,—that is, to first close the door, then insert the plug, and then close the switch.

20 It will be noted that the latch 60 is up near the top of the box where it is not readily accessible. The advantage of this arrangement is that it makes it difficult for the attendant to get at the latch to deliberately raise it while the door is open 25 and thus defeat the purpose of the latch.

It will be understood that the actual form 30 of the parts may be considerably varied without departing from the spirit of the invention. It will also be understood that it is not essential that all of the elements 35 of the device be present in order to produce an operative and useful structure. For example, the door locking mechanism may be omitted without destroying the coöperative effect of the lug 40 with the dog 47. Similarly, the latch 60 may be omitted without 40 destroying the ability of the coöperating hooks 56, 57, to hold the door locked so long as the plug remains within the receptacle.

In the accompanying claims I do not wish 45 to be understood as employing the terms "plug" and "receptacle" in the unduly restricted sense that the receptacle is the chambered part and that the plug has a portion 50 entering into it. I employ the terms in the broader sense that the receptacle is the stationary part and the plug the removable one.

Having thus described my invention what 55 I claim as new and desire to secure by Letters Patent, is:—

1. Electric apparatus comprising a throw switch, a box inclosing said switch, a receptacle carried by said box, a plug for said receptacle, the receptacle having a longitudinal slot and the plug having a lug sliding in said slot whereby the plug is non-reversible, a dog adapted to move into and 60 out of the path of the lug for blocking its movement, a handle for operating said dog, and means operated by said handle and adapted to coördinate the switch with the dog for moving the dog into acting position 65 when the switch is closed.

2. In a device of the class described, the combination of a switch box, a door for closing it, a receptacle carried by the box, a plug for the receptacle, and locking means for holding the door closed, said locking 70 means being held by the plug in acting position when the plug is in position within the receptacle, whereby the door cannot be opened without first withdrawing the plug.

3. In combination, a switch box, a door 75 for it, a locking arm, adapted when in raised position to engage the door for locking it, a receptacle, and a plug for the receptacle, said plug being adapted to hold the locking arm raised in locking position, 80 when the plug is in the receptacle.

4. In a device of the class described, the combination of a switch, a box inclosing it, a door for the box, a receptacle carried by the box, a plug for the receptacle, and locking 85 means for holding the door closed, said locking means being held in acting position when the plug is in position in the receptacle, said locking means being adapted to unlock the door when the plug is withdrawn and said locking means being also adapted when thus released by the plug to automatically engage the switch and lock it in open position when said switch has been moved to open position. 90

5. A combined switch and receptacle comprising a box, a switch mounted therein, a door hinged to the box, a latch within the box adapted to hold the switch open, means operated by the door for lifting the latch 100 when the door is closed and thus releasing the switch so that it may be closed, a receptacle carried by the box, a plug for entering said receptacle, and a lockout adapted to hold the switch in open position, said lockout being adapted to release the switch when the plug is inserted into the receptacle, whereby the door must be closed and the plug inserted before the switch can be closed. 105

6. A combined switch and receptacle comprising a box, a switch mounted therein, a door hinged to the box, a latch within the box adapted to hold the switch open, means operated by the door for lifting the latch when the door is closed and thus releasing the 110 switch so that it may be closed, a receptacle carried by the box, a plug for entering said receptacle, a lockout adapted to hold the switch in open position, said lockout being adapted to release the switch when the plug 115 is inserted into the receptacle, whereby the door must be closed and the plug inserted before the switch can be closed, and a handle located outside the box, and having connections passing through the wall of the box 120 and adapted to engage the switch to thereby enable the operator to close the switch after the door has been closed and the plug inserted. 125

7. A combined switch and receptacle com- 130

prising a box, a switch mounted therein, a door for the box, a receptacle carried by the box, a plug for entering said receptacle, a door lock controlled by the plug and adapted to hold the door locked when the plug is inserted, a dog for preventing the withdrawal of the plug, and means moving in harmony with the switch for moving the dog to non-acting position as the switch moves open, whereby the switch must be open before the plug can be withdrawn and the door cannot be opened until the plug is withdrawn.

8. A combined switch and receptacle comprising a box, a switch mounted therein, a door for the box, a receptacle carried by the box, a plug for entering said receptacle, a door lock controlled by the plug and adapted to hold the door locked when the plug is inserted, a dog for preventing the withdrawal

of the plug, an arm connected to the switch and moving in unison therewith for moving the dog to non-acting position when the switch moves open, and a handle located outside of the box and connected to the switch for opening it.

9. In a device of the class described, a switch, a receptacle, a plug for the receptacle, a box inclosing the switch, a handle outside of the box connected to the switch for closing it, a lug on the side of the plug, and an arm adapted to engage said lug when the plug is in an intermediate position in the receptacle, to thereby prevent the handle from closing the switch.

In witness whereof I have hereunto subscribed my name.

JOHN LOFGREN.
